UNITED STATES PATENT OFFICE

2,452,594

METHOD OF REFRIGERATION EMPLOYING
DRY ICENathan Morris, Silver Spring, Md., assignor, by
mesne assignments, to American Instrument
Co., Inc., a corporation of Maryland

Application May 5, 1944, Serial No. 534,314

8 Claims. (Cl. 62—170)

1

My invention relates broadly to refrigeration and more particularly to a method of producing controlled sub-zero temperatures.

One of the objects of my invention is to provide a method for producing controlled temperatures of the order of 130° below zero and lower.

Another object of my invention is to provide a method of producing controlled temperatures from solid refrigerants considerably below the lowest temperature limit of the solid refrigerants.

Still another object of my invention is to provide a method of producing temperatures considerably below the lowest temperature limit of solid refrigerants employed in the refrigeration system.

A further object of my invention is to provide a method of dehumidifying air, precooling the air and scrubbing the surface of a solid refrigerant with the precooled dehydrated air for continuously removing surface gases which normally enclose the solid refrigerant for producing extremely low temperatures.

A still further object of my invention is to provide a method of refrigeration utilizing Dry Ice in which the surface of the Dry Ice which is normally surrounded by an insulating blanket of CO₂ gas is continuously scrubbed by a dehydrated medium at such velocity that the insulating effects of the CO₂ gas are continuously removed for producing an extremely low temperature.

Other and further objects of my invention reside in a novel method of refrigeration for producing sub-zero temperatures from Dry Ice as set forth more fully in the specification hereinafter following by reference to the accompanying drawings, in which:

Figure 1 schematically illustrates one form of apparatus for carrying out the method of my invention; Fig. 2 is a fragmentary view of the method of directing dehydrated air against the solid CO₂ in the temperature controlled cabinet; and Fig. 3 represents a typical control circuit for the apparatus used in carrying out the method of my invention.

The lowest maximum temperature of Dry Ice, a solid refrigerant, is approximately 109° F. below zero. When Dry Ice is used as a refrigerant with ordinary methods of control it is impracticable to obtain accurate control of temperatures below —90° F. I have utilized Dry Ice as a refrigerant in chilling and heat treating systems in temperature control cabinets of the type set forth in my copending application Serial No. 532,807, filed April 26, 1944, entitled Refrigeration apparatus, for various processes such as instrument testing, aircraft equipment testing, mate-

2

rial testing for determining durability, performance, etc., at low temperatures; the conditioning of metals including the chilling of aluminum rivets to retard age hardening and to keep them soft enough for driving; in the storing of serums, blood chemicals, etc.; in the treating of tool and other steels to produce desired characteristics otherwise difficult to obtain by ordinary methods of treatment for accelerating the ageing of metals; in food freezing and in many other commercial applications. In the course of my development I have discovered that extremely low sub-zero temperatures can be produced well below the maximum lowest temperature generally

attributed to Dry Ice by utilizing the Dry Ice in special manner. I employ a refrigeration cabinet structure of the kind set forth in my copending application Serial No. 532,807, supra, which is provided with all of the controls explained therein which will normally control temperatures to approximately 100° F. below zero. In addition to the normal controls I employ, I provide means auxiliary to the temperature controlled cabinet for dehydrating air for removing substantially all moisture from the air; precooling the dehydrated air for lowering the air temperature before it enters the temperature controlled cabinet; and distributing the dehydrated precooled air at a predetermined velocity over Dry

Ice within the temperature controlled cabinet for scrubbing the surface of the solid carbon dioxide or Dry Ice with dry air that removes the surface of gas that normally tends to collect about the solid Dry Ice thereby causing the Dry

Ice to produce lower temperatures. The CO₂ gas that collects around the solid carbon dioxide or Dry Ice and surrounds the Dry Ice in all directions constitutes an insulating blanket or envelope that limits the effective temperature of the Dry Ice with respect to the surrounding gas. In the process of my invention I direct dehydrated air at such a velocity against the surfaces of the Dry Ice that the insulating blanket of CO₂ gas is continuously removed at a rapid rate. This process results in the creation of lower temperatures.

The important step is to remove moisture from the air that is directed against the Dry Ice. If such moisture is not removed a coating resembling snow rapidly deposits upon the Dry Ice serving as an effective insulator against the production of any temperatures in surrounding media lower than the lowest temperature limit of the Dry Ice. Referring to the drawings in more detail, reference character 1 designates a blower which collects and directs air to the dehydrator and

precooler represented at 2. The blower is driven by motor 3 which may be connected to any suitable source of power such as 110 volt 60 cycle alternating current. The air delivered by blower 1 is forced through pipe 4 into the precooler 2. For purposes of explaining the method of carrying out my invention all of this equipment is illustrated schematically and it will be understood that I am not limited to the particular equipment shown or arrangement of equipment shown and that the apparatus shown is to be considered in the illustrative sense and not in the limiting sense. As illustrated, the precooler comprises a cylindrical member 5 containing a multiplicity of spaced parallel plates which alternate in their effective area so that plate 6 directs the air around the peripheral edges thereof as represented at 6a. The next succeeding plates repeat the arrangement heretofore explained, thereby providing a serpentine path for the air through the cylinder 5. The outlet for cylinder 5 is represented by pipe 8 connected to the end of cylinder 5. The schematic view shown is substantially a horizontal sectional view in which the cylinder 5 is enclosed in the insulation jacket represented at 9. The cylinder is packed in Dry Ice represented at 10. The solidified CO₂ blocks are packed around the cylinder in such manner that a sub-zero temperature is imparted to the cylinder 5. This sub-zero temperature is conducted into the metallic parts of the cylinder 5, lowering the plates 6 and 7 to a sub-zero temperature so that the air which is forcibly projected into cylinder 5 is dehumidified, that is, the moisture content in the air is substantially removed. The plates 6 and 7 are cooled by the Dry Ice to such a low temperature that the water vapor in the air condenses on the plates as frost or snow so that the air emerges at the outlet 8 substantially dry and free of moisture and at a sub-zero temperature which may be of the order of -109° F. which is the temperature of the solidified CO₂ blocks indicated at 10. The precooled dehydrated air at sub-zero temperature then enters the manifold 11 within the temperature controlled cabinet represented generally at 12. The temperature controlled cabinet is explained more fully in my copending application Serial No. 532,807, supra, as including Dry Ice compartment 14 and a work compartment 15 separated by partition 16. The Dry Ice compartment 14 contains mounting means for a multiplicity of trays that I have shown generally at 17, 18 and 19 in Fig. 2. Each of the trays contains open work shelf-like supports as shown at 20, 21 and 22 for the blocks of solidified Dry Ice CO₂ illustrated for example at 23. Both the bottom and cover portions of the trays 17, 18 and 19 are provided with deflector members represented at 17a and 17b, and 18a and 18b, and 19a and 19b. These deflectors serve as guides to direct the air at high velocity against the surfaces of the blocks of Dry Ice 23. The high velocity air is directed against the blocks of Dry Ice and guided by the deflectors by reason of the supply of the air at high velocity through manifold 11 and the multiplicity of horizontally extending distributor pipes designated at 24, 25, 26, 27, 28 and 29 in Fig. 2. The arrangement of the trays in superimposed relation is entirely schematic and may be varied to meet necessary conditions but is intended to illustrate one method by which a relatively large surface area of solidified CO₂ may be scrubbed with dehumidified and precooled air at high velocity.

It will be observed that the air is directed through apertures 17d, 18d and 19d in one wall of each of the superimposed trays and is discharged through apertures 17e, 18e and 19e in the opposite wall of each of the superimposed trays. It will also be observed that the high velocity flow of air takes place in the same general direction as the normal circulation of gas through the work chamber 15 as indicated by arrows 30 as referred to more fully hereinafter.

The scrubbing effect which is obtained by the blasts of air at high velocity against the surfaces of the blocks of CO₂ has the effect of removing the envelope of gas that tends to collect around the solidified block thereby producing a lowering of the sublimation temperature and permitting the blocks of CO₂ to be effective for producing sub-zero temperatures that are considerably lower than the lowest temperature to which the blocks of CO₂ normally assume. The important feature of the method of my invention is to insure the removal of moisture from the air before it is directed against the surfaces of the blocks of CO₂. The removal of moisture is effectively accomplished in the method of my invention by the precipitation of moisture through the dehydrator and precooler represented at 2.

The arrangement of the work chamber 15 and Dry Ice compartment 14 is more clearly explained in my aforesaid copending application Serial No. 532,807, supra, and is illustrated herein merely for the purpose of explaining the cooperation of the circulating fans and heater arranged within the cabinet structure.

In Fig. 1 the blower which I provide for the intermittent circulation of gas is illustrated at 31 driven by motor 32 arranged externally of the insulated cabinet structure 12 and operative to draw gas from the blocks of CO₂ represented at 23 in the several superimposed trays 17, 18 and 19 and force the gas through duct system 33 into the work compartment 15. A valve 34 is located in partition 16 for controlling the volume of gas pumped from the Dry Ice compartment 14 into the work compartment 15.

In addition to the blower 31 there is the circulating fan 35 arranged beneath the Dry Ice compartment and in the work compartment and driven by the externally mounted motor 36 supplied with power from line circuit 41. Fan 35 serves to continuously circulate the gases within the work compartment 15 and pump the gases through the multi-section heater coils 37 and 38 which may be selectively connected in series or parallel or isolated in a single effective section by means of selector switch 39 represented in the schematic circuit of Fig. 3. The heater coils 37-38 are prevented from elevating the work compartment beyond a predetermined limit of temperature by means of the thermostatic circuit breaker arranged as a protective device 40 in the heater circuit. The power supply system for the control circuit is connected to line circuit 41 to which is connected the input circuit of transformer 42, the output circuit of which connects to rectifier system 43 through leads 54 which delivers direct current to the control circuit 55 of relay 44 which includes winding 45 connected in series with thermostat 46 which is subject to the temperatures within the work compartment 15. Relay winding 45 controls armature 47 which operates mercury switches 48 and 49 in opposed relation. That is to say, when the contacts of mercury switch 48 are open the contacts of mercury switch 49 are closed. Thus the heater coils 37

and 38 are activated from the power supply circuit 41 through contacts 48 according to the operation of thermostatic switch 46. Sets of contacts 49 control the circuit to the blower motor 32 so that when thermostat 46 calls for lower temperature in the work compartment, contacts 49 are closed, thus closing the circuit from the power line system 41 to blower motor 32. Manually operated switch 50 is provided for cutting motor 32 out of the circuit as may be desired. Switch 51 is provided and is movable to contact 51a for rendering switch 49 effective, or to contact 51b for rendering contacts 49 ineffective so that blower motor 32 may be operated continuously irrespective of temperature conditions called for by thermostat switch 46.

The blower 1 which forces air into the precooler 2 under control of driving motor 3 is also operated by contacts 49 as will be seen in the circuit of Fig. 3. The motor 3 that drives blower 1 is connected through circuit 52 in parallel with motor 32. A separate manually controlled switch 53 is provided in circuit with motor 3 so that motor 3 may not be operated at the same time that motor 32 is operated. Thermostat 46 may thus be set for sub-zero temperatures of approximately the order of -109° F. which may be attained within work compartment 15 by intermittent operation of blower 31. If, however, extremely low sub-zero temperatures are required of the order, for example, of -139° F. then with thermostat 43 set for such sub-zero temperatures, switch 53 is closed so that blower motor 3 is also operated simultaneously with blower motor 32, thus driving blower 1 and forcing air through the dehydrator and precooler 2 to the distributor system 11 and through the distributing nozzles over the blocks of Dry Ice for scrubbing the insulating blanket of CO_2 gas that surrounds the blocks of CO_2 away from the surfaces, thereby permitting the production of lower sublimation temperatures. This forces the temperature of the work compartment to a very low sub-zero temperature achieving the production of temperatures lower than the normal operating temperature of solidified CO_2 .

While I have described my invention in one of its preferred embodiments I realize that changes in details of the method and arrangement of apparatus for carrying out the method may be employed and I intend no limitations upon my invention other than may be imposed by the scope of the appended claims.

What I claim as new and desire to secure by Letters Patent of the United States is as follows:

1. The method of effecting refrigeration with solidified CO_2 at sub-zero temperatures which comprises dehydrating air, precooling the dehydrated air and blowing the precooled dehydrated air over the surface of solidified CO_2 in a confined temperature controlled area at a velocity sufficient to maintain the solidified CO_2 free from the collection of gas over the surface area thereof.

2. In a system of refrigeration employing solidified CO_2 in a confined temperature controlled cabinet, the method of maintaining sub-zero temperatures within a temperature controlled cabinet which comprises forcibly flowing dehydrated air into a confined temperature controlled cabinet, precooling the air before entry into the temperature controlled cabinet and distributing the dehydrated precooled air within the temperature controlled cabinet over the surface of solidified CO_2 for preventing the accumulation of

a blanket of insulating gas around the surface of the solidified CO_2 and creating a sublimation temperature lower than the lowest temperature limit of the solidified CO_2 .

- 5 3. In a system for producing sub-zero temperatures in a temperature controlled confining cabinet employing solidified CO_2 as a refrigeration medium, the method of producing sub-zero temperatures which comprises forcibly flowing air
- 10 into the temperature controlled cabinet, removing moisture from the air and precooling the air to sub-zero temperatures before the air enters the temperature controlled cabinet, and directing the air at high velocity over the surface of solidified
- 15 CO_2 within the temperature controlled cabinet at a velocity sufficient to eliminate the formation of blankets of insulating gas around the solidified CO_2 for creating extremely low sublimation temperatures.
- 20 4. In a refrigeration system employing solidified CO_2 as a refrigerating medium within a temperature controlled cabinet, the method of producing sub-zero temperatures within the cabinet which comprises forcibly flowing air into the
- 25 temperature controlled cabinet, dehydrating the air and lowering the temperature of the air to sub-zero temperatures before entry into the temperature controlled cabinet and forcibly flowing the dehydrated precooled air over the surface of
- 30 the solidified CO_2 within the temperature controlled cabinet for continuously preventing the formation of blankets of insulating gas around the solidified CO_2 .
- 35 5. In a refrigeration system employing solidified CO_2 as a refrigerating medium within a temperature controlled cabinet, the method of producing sub-zero temperatures within the cabinet which comprises forcibly flowing air into the temperature controlled cabinet, dehydrating the
- 40 air and lowering the temperature of the air to sub-zero temperatures before entry into the temperature controlled cabinet and forcibly flowing the dehydrated precooled air at predetermined velocity over the surface of the solidified CO_2
- 45 within the temperature controlled cabinet, scrubbing the surface of the solidified CO_2 within the temperature controlled cabinet for continuously removing the insulating blanket of CO_2 gas that tends to collect around the solidified CO_2 whereby
- 50 by the solidified CO_2 is effective to produce sub-zero sublimation temperatures within the temperature controlled cabinet.
- 55 6. The method of effecting refrigeration with solidified gas at sub-zero temperatures which comprises dehydrating air, precooling the dehydrated air and blowing the precooled dehydrated air over the surface of solidified gas in a confined temperature controlled area at a velocity sufficient to maintain the solidified gas free from an insulating envelope of gas over the surface thereof.
- 60 7. In the art of refrigeration employing solidified gas in a confined temperature controlled cabinet, the method of maintaining sub-zero temperatures within said temperature controlled cabinet which comprises forcibly flowing air into a confined temperature controlled cabinet, precooling the air before entry into the temperature controlled cabinet and distributing the dehydrated precooled air within the temperature controlled cabinet over the surface of solidified gas for preventing the accumulation of a blanket of insulating gas around the surface of the solidified gas, thereby creating a sublimation temperature
- 65
- 70
- 75

lower than the lowest temperature limit of the solidified gas.

8. In a system for producing sub-zero temperatures in a temperature controlled confining cabinet employing solidified gas as a refrigeration medium, the method of producing sub-zero temperatures which comprises forcibly flowing air into the temperature controlled cabinet, removing moisture from the air and precooling the air to sub-zero temperatures before the air enters the temperature controlled cabinet, and directing the air at high velocity over the surface of solidified gas within the temperature controlled cabinet at a velocity sufficient to eliminate the formation of blankets of insulating gas around the solidified gas for creating extremely low sublimation temperatures.
